UNITED STATES PATENT OFFICE

ROBERT L. CLARK, OF OSHKOSH, WISCONSIN

GAME BOARD

Application filed May 20, 1931. Serial No. 538,830.

This invention relates to games and more particularly to game boards of the type with which playing pieces are movable about the surface of the game board and controlled by opposing players.

A primary object of the invention is to resiliently support the board so that a player by altering the position of the board from the horizontal may determine the course of a ball rolling on its surface.

Another object of the invention is to construct such a board that the successful operation of the game will be dependent upon the skill rather than upon the superior strength of the players.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 is a top plan view of a game board constructed in accordance with this invention;

Fig. 2 is a transverse section thereof;

Figs. 3 and 4 are perspective views respectively of two of the playing pieces used; and

Fig. 5 is a similar view of a ball used in connection with the game.

In the embodiment illustrated, a board 1 is provided which may be of any desired configuration and is here shown circular in shape and having a circumscribing flange 2, a portion of which projects above the top of the board and a portion below. The projecting portion or skirt 3 which extends below the board operates as a stop for limiting the compressing or tilting movement of the board in a manner presently to be described.

The board 1 is supported by a plurality of compressible feet 4, six of which are here shown arranged adjacent the periphery of the board and circumferentially spaced in relation to each other. These feet 4 as shown

are made of sponge rubber although obviously they may be constructed of any other resilient material. This mounting of the board on the feet located adjacent the periphery provides for altering the horizontal position of the board by downward pressure exerted at points along the rim, the board returning to normal position after the pressure has been removed. The game board here shown is designed to be used in connection with checker-like men 5 and 6 which are of different colors and each player has the same number of men which are placed in the same relative position on the board as his opponent. After the men have been set on the board the ball 7 which is preferably about five-eighths of an inch and preferably made of steel is set in the center of the board or given a throw around the rim of the board to place it in play. Any player may then at any time press down upon any part of his portion of the board rim thereby changing rapidly the point of pressure and causing the ball to strike his opponent's men. The first player to count out loud a set number of strikes, for instance, 15, wins that game. Any successive strike on the same man does not count unless the ball first strikes the rim or any other man on the board.

The compressible feet 4 of sponge rubber or any other suitable material permit the players by using their hands to apply and release downward pressure on the rim of the board thereby affecting the course of a ball rolling over its surface and which is designed for use in playing a game.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

A game board having a circumferential flange extending above and below the top and bottom faces thereof to form respectively a piece or ball retaining rim and a tilt controlling stop, said board having a plurality of spaced compressible and expansible feet depending from its lower face adjacent its periphery whereby the board may be tilted by slight pressure exerted adjacent its periphery without moving it from its support.
